[57] **CLAIM**

The ornamental design for a combined package and dice game, as shown and described.

DESCRIPTION

FIG. 1 is a perspective view of a combined package and dice game showing our new design;

FIG. 2 is a perspective view of the dice cup for clarity of illustration;

FIG. 3 is a top plan view of FIG. 2;

FIG. 4 is a bottom plan view of FIG. 2;

FIG. 5 is a front perspective view of a die; and,

FIG. 6 is an inverted rear perspective view of FIG. 5;

FIG. 7 is a front perspective view of another die; and,

FIG. 8 is an inverted rear perspective view of FIG. 7.
The undisclosed other 3 dice are similar in appearance to that disclosed.
